(57) **CLAIM**

The ornamental design for a balloon and rod connector combined with the rod, as shown and described.

DESCRIPTION

Notice: More than one reissue application has been filed for the reissue of Pat. No. D-529,102. The reissue applications are application Ser. Nos. 29/286,205 (the present application), and 29/322,997, which is a divisional of reissue of the present application.

FIG. 1 is a perspective view showing my new design with the rod portion removed for a clear disclosure of the end configuration;

FIG. 2 is a reduced scale front elevational view thereof;

FIG. 3 is a rear elevational view thereof;

FIG. 4 is a left side elevational view thereof;

FIG. 5 is a right side elevational view thereof;

FIG. 6 is a top view thereof; and,

FIG. 7 is a bottom view thereof; and,

FIG. 8 is an enlarged scale perspective view of the cross section along line 8—8 of FIG. 3].

1 Claim, 3 Drawing Sheets

(AMENDED)

Matter enclosed in heavy brackets [ ] appears in the original patent, but forms no part of this reissue; matter printed in italics indicates the additions made by reissue.
